UNITED STATES PATENT OFFICE.

FREDERICK C. COSEO, OF COLUMBUS, OHIO, ASSIGNOR TO THE JEFFREY MANUFACTURING COMPANY, OF COLUMBUS, OHIO, A CORPORATION OF OHIO.

LIQUID-FUEL TANK.

1,132,833.

Specification of Letters Patent. Patented Mar. 23, 1915.

Application filed September 25, 1912. Serial No. 722,359.

To all whom it may concern:

Be it known that I, FREDERICK C. COSEO, a citizen of the United States, residing at Columbus, in the county of Franklin and 5 State of Ohio, have invented certain new and useful Improvements in Liquid-Fuel Tanks, of which the following is a specification, reference being had therein to the accompanying drawing.

10 The invention relates to fuel tanks of the sort adapted for use on vehicles the motors of which receive their energy from liquid fuel. The fuel may be used either in a motor of the internal combustion type or under a 15 boiler to generate steam.

The principal object of the invention is to provide a tank having discharge connections arranged to insure the retention of a reserve supply of fuel which can be released only 20 by the action of the operator.

Another object is to provide automatic means for positively preventing the filling of the tank above a certain predetermined level.

25 Other objects will be apparent from the following specification and claims.

A fuel tank embodying my invention is especially well adapted for use in connection with gasoline locomotives intended for 30 use in and about mines. As is well known there is great danger in mines, especially coal mines, of explosions resulting from the ignition of a gaseous or dusty atmosphere. On account of this danger of explosion it is 35 essential that the gasoline tank of the locomotive be filled outside of the mine. If it were filled inside there would be great danger of the resulting gasoline vapors becoming ignited and setting fire to the explosive 40 mine atmosphere. By means of a device embodying my invention the operator is always assured that after the main gasoline supply has become exhausted he will have sufficient gasoline in his reserve supply to 45 make the run to the filling station outside of the mine.

50 Of the drawing—Figure 1 is a cross-sectional view through a fuel tank embodying one form of my invention. Fig. 2 is a cross-sectional view through a fuel tank embodying another form of my invention.

55 Referring to Fig. 1 of the drawing, 1 re-

resents as a whole the main body of the tank, which may be formed of sheet metal as shown, or in any other desired way. In the top wall of the tank there is an aperture in which is mounted a frame 2 secured in place by rivets 3. To the frame 2 there is bolted a plate 4 having a threaded aperture 5 into which is screwed the end of the filling pipe 6. At the lower side of the plate 4 there is a large threaded recess which registers with the aperture 5. At the inner side of this recess there is a strainer 7 which is held in place by a threaded ring 8 having at its lower side an inward projecting annular flange. Positioned within the ring 8 and above the horizontal flange thereof is a valve closure 9 having a depending stem 10. Pivoted to the lower end of the stem 10 is a lever 11 which is pivotally connected at 12 to the plate 4. The other end of the lever 11 carries a cork float 13, the weight of which is sufficient to lift the valve closure 9, but which has sufficient buoyancy when 75 immersed in the liquid fuel to press the valve closure closely against the flange of the ring 8 to cut off the passage through the aperture 5 and the pipe 6.

80 Formed at the upper side of the plate 4 is a vent chamber 14 which is closed at the top by means of a valve 15 which has depending slotted guide fingers 16. A cotter pin 16a passes through the slots of the guide fingers and serves to limit the movement of the 85 valve. This valve has sufficient weight to close the vent against the admission of air and dust but not enough to interfere with the outward flow of air during the filling of the tank.

90 In the bottom wall of the tank there is an aperture in which is mounted a flange 17 held in place by rivets 17a. Secured to this flange 17 is a plate 18 provided with two threaded apertures 19 and 20. Into these 95 apertures 19 and 20 there are fitted pipes 21 and 22 which connect by means of a two-way valve 23 with a pipe 24 which leads to the carburetor or other device for utilizing the fuel. It will be seen that by means of the valve 23 either of the pipes 21 and 22 may be connected with the pipe 24. One of the apertures in the plate 18, as for instance 19, extends upward through a boss 25 so

that its upper end is at a level considerably above the upper end of the other aperture 20. At the upper end of the aperture 20 there is provided a valve needle 26 which is 5 adapted to entirely close the aperture. Pivotally connected to the upper end of the needle 26 is a lever 27 which is pivoted at 28 to the plate 18. The other end of the lever 27 carries a float 29. When the tank is partially filled the buoyancy of the float 29 10 serves to force the needle 26 downward to entirely cut off the passage through the aperture 20. However, when the level of liquid in the tank falls below a certain level, the float 15 assumes a position such that the needle 26 is held away from its seat and the aperture 20 is opened.

In operation, when it is desired to fill the tank the operator simply pours gasoline or 20 other fuel into the funnel from which it flows through the pipe 6 and the aperture 5 around the valve closure 9 into the tank, it being understood that the valve closure is held off from its seat by the float 13. How- 25 ever, as soon as the tank becomes filled the float 13 is elevated and the valve closure 9 is drawn down against its seat and the further flow of liquid into the tank is prevented. Because of this automatic valve it is impos- 30 sible for the operator to flood or overflow the tank. During the filling operation, the air in the tank can freely pass out under the valve 15. However, this valve is normally held closed by its own weight and prevents 35 the flow into the tank of air or dust. When the tank is filled the float 29 holds the needle 26 in position to close the aperture 20. Therefore, in order to get a flow of fuel to the carbureter the valve 23 must be set to 40 provide communication through the pipe 21. The fuel flows out through the pipe 21 until the level in the tank is lowered to the upper end of the aperture 19. When this level has been reached the float 29 will have been 45 lowered to such an extent that the needle 26 will have been lifted from its seat, thus opening the aperture 20. As soon as there is a failure of gasoline to flow through the aperture 19 and the pipe 21 the operator 50 simply turns the valve 23 to make connection with the pipe 22. The gasoline in the tank below the level of the upper end of the aperture 19 then becomes available and this is sufficient to enable the locomotive or other 55 vehicle to run to a place where the tank can be refilled. It will be observed that upon refilling, the float 29 again closes the aperture 20, thus making it absolutely necessary for the operator to again turn the valve 23 to 60 connect the pipe 21 with the pipe 24.

In Fig. 2 I have shown a modified form of my invention. In this view I have shown a tank having a partition 30 which divides the tank into two unequal parts 31 and 32.

The pipe 21 communicates with the larger 65 part 31, and the pipe 22 with the smaller part 32, each pipe preferably terminating at the bottom of the tank. The valve needle 26 for the pipe 22 is controlled by the float 29^a which is located in the part 31 of the 70 tank. The float 29^a may be connected with the valve needle 26 by means of the lever 27^a pivoted to the partition 30 at 28^a and connected with the valve needle by means of the link 27^b.

It will be clear that the operation of the device as shown in Fig. 2 is substantially the same as that of the device shown in Fig. 1. The valve 26 is held closed so long as there is a supply of fuel in the part of the 80 tank with which the pipe 21 communicates. It is only after the fuel in this part of the tank has been exhausted or nearly exhausted that any fuel can be drawn from the part of the tank with which the pipe 22 communicates. The operator, therefore, must after filling the tank turn the valve 23 to cut off the pipe 22 and connect the pipe 21 before he can get any flow of fuel to his carbureter. After the supply in the part 31 is 90 exhausted then the supply in the part 32 can be made available by throwing the valve 23 to connect the pipe 22 and disconnect the pipe 21.

I am aware that it has been before proposed to provide a reserve supply of liquid fuel which can be used by throwing a valve, but in all of the earlier devices with which I am familiar, it has been possible for the operator, either carelessly or intentionally, 100 to leave the valves so positioned that the supposed reserve supply is used either before or simultaneously with the main supply. In the device embodying my invention, however, the automatic needle valve 26 prevents 105 the use of the reserve supply until the main supply has been entirely exhausted.

What I claim is:

1. In a device for containing and supplying liquid fuel, the combination of a fuel 110 container, a discharge duct communicating with the container at one point, a second discharge duct communicating with the container at another point, means for preventing a part of the fuel in the container from 115 flowing out through the first duct, a manually controllable valve for connecting either duct with an outlet pipe, and a valve controlled by the level of the fuel in the container for closing the second duct so long as 120 there is sufficient fuel to flow out through the first duct and for opening the second duct when the supply of fuel which can flow out through the first duct is exhausted.

2. In a device for containing and supplying liquid fuel, the combination of a tank, two discharge ducts communicating with the tank at different levels, a manually con-

trollable valve for connecting either duct with an outlet pipe, and a valve automatically controlled by the level of the fuel in the tank for closing the lower duct when the
5 fuel level is above the opening to the upper duct and for opening the lower duct when the fuel level is below the said opening.

In testimony whereof I affix my signature, in presence of two witnesses.

FREDERICK C. COSEO.
